(57) **CLAIM**

The ornamental design for a cabinet, as shown.

DESCRIPTION

FIG. 1. is a front view of a cabinet showing my new design thereof;

FIG. 2. is a rear view thereof;

FIG. 3. is a left side view thereof;

FIG. 4. is a right side view thereof;

FIG. 5. is a top plan view thereof;

FIG. 6. is a bottom plan view thereof; and,

FIG. 7. is a perspective view thereof.

The broken lines shown in the drawings are for the purpose of illustrating portions of the article and form no part of the claimed design.

1 Claim, 7 Drawing Sheets
